UNITED STATES PATENT OFFICE

EDWIN LUNDGREEN, OF FREDERICK, MARYLAND, ASSIGNOR TO COMBUSTION ENGINEERING CORPORATION, OF NEW YORK, N. Y., A CORPORATION OF NEW YORK

ART OF STEAM GENERATION

Application filed January 16, 1925. Serial No. 2,731.

This invention relates to the generation of steam and is especially useful in connection with stoker fired boiler furnaces in association with sinuous header type boilers and it is in connection with such an installation that it will be described.

I propose to supplement the boiler by boiler tubes arranged to define a substantial part of the combustion chamber such tubes therefore being very largely subject to radiant heat by virtue of which the size of the boiler proper may be very materially reduced. By such a construction I am enabled to operate the boiler at greatly increased rates, in comparison to standard practice and design.

One of the primary objects of my invention, therefore, is to provide a boiler and furnace in which the rate of evaporation may be increased whereby more steam may be generated from an installation of standard size or in other words of generating a given amount of steam from a smaller installation than possible under existing methods.

A more specific object of my invention is to provide evaporating surfaces around the combustion space of the furnace connected for circulation to various portions of a sinuous boiler whereby circulation within such evaporating surfaces will not interfere with the circulation of the boiler as a whole.

Another object is the provision of means whereby circulation within some of the evaporating surfaces is established by the particular arrangement of the tubes forming such evaporating surfaces.

Still another object is to provide refractories for some of the tubes defining the combustion space arranged with respect to the tubes so as to effect circulation.

Still another object is to so arrange the boiler so that the refractory structure of the furnace may be greatly simplified and cheapened and the life thereof greatly extended.

How the foregoing, together with such other objects and advantages as may herein-after appear, or are incident to my invention, are realized, is illustrated in preferred form in the accompanying drawings wherein:

Fig. 1 is a vertical section through an installation embodying my invention;

Fig. 2 is a section taken substantially on the line 2—2 of Fig. 1;

Fig. 3 is a fragmentary plan section taken on the line 3—3 of Fig. 1; and

Fig. 4 is a fragmentary cross section taken on the line 4—4 of Fig. 1.

Referring to the drawings the reference character A denotes a combustion space in which the fuel is burned, the reference character B, a stoker typical of any one of a number of similar stokers to which air is supplied under pressure, and C, a sinuous header type boiler located above the combustion space A.

The combustion space A is defined on its four vertical sides by sets of water tubes 1, 2, 3 and 4. The sets of tubes 1 and 2 extend substantially horizontally of the combustion space and at opposite sides thereof each connecting into a pair of upright sinuous headers 5 and 6 which headers are connected by suitable means 7 to the end header sections 8 of the sinuous header type boiler C.

The sets of tubes 3 and 4 are each composed of a double row of upright tubes 9 and 10 and define the two other vertical sides of the combustion space. Each set of tubes 3 and 4 connects its upper header 11 to its lower header 12 which headers are common to the two rows of tubes making up each set. The upper headers 11 are connected by suitable means 13 to various header sections of the boiler C.

The headers 6 and their connections 7 constitute downcomers and the sets of tubes 1 and 2 constitute upcomers, by virtue of their inclination, of the circulatory system. The headers and their respective connections are of a size such as not to retard the rapid circulation produced by the exposure of the sets of tubes 1 and 2 to the radiant heat. By combining this arrangement with a sinuous header type boiler I am enabled to connect the headers 5 and 6 of the sets of tubes 1 and 2 into particular sections of the boiler without interfering with the circulation of the balance of the boiler.

Referring now to the arrangement of the sets of tubes 3 and 4 it will be seen that the tubes comprising each set are arranged in two rows with the tubes of the row 10 toward the

outside of the boiler directly in back of the tubes 9 of the inner row, by virtue of which the outer tubes are shaded by the inner row. Stated in another way, the inner tubes 9 will absorb radiant heat very rapidly while the outer tubes 10 will be protected or shaded from such heat. Thus the outer row of tubes will function as downcomers and the inner row as upcomers whereby circulation is created within said tubes. As before stated these tubes are provided with headers, the upper of which are connected to various sections of the sinuous header type boiler C thus connecting them into the circulating system of the boiler.

Hence the advantages hereinbefore pointed out in connection with the set of tubes 1 and 2 also becomes apparent in connection with the sets of tubes 3 and 4.

When desirable to further insure proper circulation additional shading of the outer rows of tubes 10 may be provided by locating refractories 14 between the rows of tubes 9 and 10.

Fig. 3 shows the rear tubes 10 enclosed in tiles 15. Thus it will be seen that these tubes 10 besides acting as downcomers by virtue of their being screened or shaded by the tubes 9, also cool the tiles 15 as do the tubes 9, so that the maintenance from erosion or high temperatures will be considerably decreased.

It is to be noted that combustion will not be destroyed by the chilling effect of the rapid absorption of heat by the tubes defining the combustion space, because of the live bed of coal and the air introduced with the fuel.

I claim:

A boiler and furnace including two sets of substantially horizontal tubes, a pair of headers for each set, two sets of upright tubes, a pair of headers for each set, each upright set comprising a double row of tubes having refractory material therebetween, one row being shaded by the other and by said refractory material and all defining the four upright walls of the combustion chamber, a boiler located above said chamber, connections between the first mentioned headers and the boiler, connections between the upper headers of the second mentioned pair of headers and the boiler, and means for admitting fuel to the combustion chamber.

In testimony whereof, I have hereunto signed my name.

EDWIN LUNDGREN.
